UNITED STATES PATENT OFFICE.

OTTO JUNG, OF JERSEY CITY, NEW JERSEY.

MACHINE FOR GRINDING SPHERICAL BODIES.

SPECIFICATION forming part of Letters Patent No. 392,435, dated November 6, 1888.

Application filed February 11, 1888. Serial No. 263,723. (No model.)

To all whom it may concern:

Be it known that I, OTTO JUNG, of Jersey City, in the county of Hudson and State of New Jersey, have invented certain new and useful Improvements in Machines for Grinding Spherical Bodies, of which the following is a specification.

This invention relates to an improved machine for grinding spherical bodies, such as balls of metal, ivory, hard rubber, composition, &c., used for anti-friction bearings, valves, casters, and other purposes in which a true sphere is required. The machine is adapted for grinding different sizes of spherical bodies and performs its work in a regular and speedy manner.

The invention consists of a machine for grinding spherical bodies, and comprises a rotatory horizontal disk provided with a circular groove or depression for the balls to be ground, and a second similarly-grooved disk that rests on the top of the walls, and means for preventing the turning of the upper disk, which means are adapted to adjust themselves to different distances of the top disk from the lower rotatory disk, according to the diameters of the balls to be ground off.

In the accompanying drawings, Figure 1 represents a front elevation, partly in vertical section, through the grinding-disks of my improved machine for grinding spherical bodies. Fig. 2 is a side elevation of the same; and Fig. 3, a plan view of the grinding-disks and a horizontal section on line $x-x$, Fig. 1, of the supporting-frame, part of the top grinding-disk being broken away.

Similar letters of reference indicate corresponding parts.

Referring to the drawings, A represents an upright supporting-frame, of wood or other suitable material, which is attached in any suitable manner to the wall or other upright support. To the upright supporting-frame A are rigidly attached horizontal bracket-arms B B, which carry vertical adjustable set-screws b b, having conically-tapering points, said set-screws being retained by screw-nuts b'. The pointed set-screws b b are vertically in line with each other and support a vertical shaft, C, to which rotary motion is imparted by means of a fixed and loose pulley, d d', and a motion-transmitting belt, (not shown in the drawings,)

which is transferred from the loose to the fixed pulley by a belt-shifter, D, which is applied by suitable staples, D', to the supporting-frame B, as shown in the drawings.

To the vertical rotary shaft C is splined a fixed horizontal disk, E, which is provided at its upper surface with an annular groove, e, preferably of V-shaped cross-section, in which the balls a to be ground are placed close together, so as to be in contact with each other. A second disk, E', is provided with a cylindrical hub, e', through which the shaft C passes, so that said disk E' can readily slide around the shaft without following the motion of the same. To the hub e' of the upper grinding-disk, E', is applied a ring-shaped retaining device, F, which is pivoted by screws h, located at diametrically-opposite points of the retaining device F to the hub e', the ring-shaped retaining device F being provided at one side with an arm, F², having an eye or aperture, f², into which the hook-shaped end f' of a link, F', can be passed, that is pivoted to a bracket-eye, g, of the supporting-standard A, so as to swing readily thereon as the upper grinding-disk, E', moves up or down. The link F' holds the upper grinding-disk, E', in a stationary position and prevents it from following the motion of the shaft C and lower grinding-disk, E, which it would otherwise do, owing to the friction exerted thereon by the balls interposed between the grinding-disks. The upper grinding-disk, E', is provided at its underside with a V-shaped or other groove, e^x, vertically above the groove e of the lower grinding-disk, E, said groove serving to retain and guide the balls which are interposed for grinding between the lower rotary and upper stationary disks.

The retaining-ring F is pivoted to the hub of the upper grinding-disk, E', by means of the pointed screws h, so as to permit the adjustment of the upper grinding-disk, E', to balls of different diameters without exerting any strain on the upper fixed grinding-disk.

The operation of the machine is as follows: Cast-metal or other balls are placed in the groove e of the lower grinding-disk, E, so as to form contact with each other. The upper disk is then placed in position on the balls. Suitable abrading medium is interposed between the disks and balls and the belt applied to the

fixed pulley of the driving-shaft C, so that a rapid rotary motion is imparted to the lower grinding-disk. By the driving action of the lower disk and the retarding action of the upper disk on the balls and the frictional contact with each other the balls are gradually ground off to a true sphere as they continually change their relative position to each other and the disks. When the balls are ground off to the proper diameter, they are then ready for use.

Having thus described my invention, I claim as new and desire to secure by Letters Patent—

1. The combination of a horizontal rotatory grinding-disk provided with an annular groove in its upper surface, an upper grinding-disk having an annular groove in its lower surface vertically above the groove of the lower disk, and a retainer for holding the upper disk in stationary position, so as to prevent it from following the motion of the rotatory disk, substantially as set forth.
2. The combination of a vertical rotary shaft, a grinding-disk fixed on said shaft and provided with a groove in its upper surface, a second grinding-disk having an annular groove in its lower surface vertically above the groove of the lower disk, the upper disk being mounted

loosely on the driving-shaft, a ring-shaped retaining device pivoted to the hub of the upper disk, and a connecting-link for connecting said retaining-ring and fixed eye, substantially as set forth.

3. The combination of an upright supporting-frame having horizontal bracket-arms, pointed set-screws supported on said bracket-arms, a vertical driving-shaft, means for imparting rotary motion to said driving-shaft, a horizontal grinding-disk fixed to said shaft and provided with an annular groove in its upper surface, a second grinding-disk placed loosely on said shaft and provided with a groove in its under surface, a ring-shaped holder pivoted to the hub of the upper driving-disk, and a retaining-link pivotally connected to an arm of the holder and a fixed eye on the supporting-frame, substantially as set forth.

In testimony that I claim the foregoing as my invention I have signed my name in presence of two subscribing witnesses.

OTTO JUNG.
